UNITED STATES PATENT OFFICE.

ROBERT E. BRESSLER, OF HAMMOND, INDIANA, ASSIGNOR TO O. F. JORDAN COMPANY,
OF EAST CHICAGO, INDIANA, A CORPORATION OF INDIANA.

RAILROAD SPREADER.

Application filed October 6, 1919. Serial No. 328,854.

To all whom it may concern:

Be it known that I, ROBERT E. BRESSLER, a citizen of the United States, and a resident of Hammond, county of Lake, and 5 State of Indiana, have invented certain new and useful Improvements in Railroad Spreaders, of which the following is a specification.

My invention relates generally to apparatus for use in constructing and maintaining railroads, and relates more particularly 10 to the spreading or distributing of soil, excavating materials, ballasting materials, and the like. In the use of a railroad spreader 15 i. e. a car having wings adapted to spread or distribute materials along the sides of the rails, it is often found desirable to perform certain other operations along the right of way, such for example, as the forming 20 of a ditch. It is convenient to carry machinery for such purposes upon the floor of the car.

It is an object of my invention to provide an improved railroad spreader, adapted 25 to run on a railroad track, and which shall be provided with wings or spreaders that shall be vertically and laterally adjustable in order to perform the work in a convenient and expeditious manner; and which 30 shall be of such construction that disposition thereof on the car can be so made that the floor of the car shall be free for the purpose of carrying any other apparatus that may be desired.

35 Further objects of my invention are to provide means of operating the spreader wings and for holding and locking them in desired operative position.

It is also an object of my invention to 40 provide mechanism, of the above character, which shall be substantially free from the necessity of manual adjustments, i. e. which shall be so constructed that the operation of the wings can be caused by men riding on 45 the car through suitable power actuated mechanism.

My invention consists generally in the form, arrangement, construction, and co-operation of the parts whereby the above 50 named objects, together with other objects that will appear hereinafter, are attainable, and my invention will be more readily understood by reference to the accompanying drawings which illustrate what I consider,

at the present time, to be the best embodiment thereof.

In said drawings:

Fig. 1 is a plan view of one end of a railroad spreader embodying my invention.

Fig. 2, is an enlarged elevation of the 60 mechanism shown in Fig. 1.

Fig. 3, is a fragmentary plan view of the mechanism for swinging the spreader wings to and from the car and for holding them in desired placed position.

Fig. 4, is an elevation of the mechanism shown in Fig. 3.

Fig. 5, is an end elevation of the mechanism shown in Figs. 3 and 4; and.

Fig. 6 is a detail sectional view substantially on the line 6—6 of Fig. 4.

In general appearance my railroad spreader resembles an ordinary flat car but inasmuch as both ends are alike or may be alike, only one end portion of the car is 75 shown. It should be understood that the car is used for railroad purposes and that in ordinary practice, a locomotive is used for moving the spreader along the track and as the car is propelled, the wings operate 80 to spread or distribute material along the sides of the rails. It should also be understood that the wings on one or both sides of the car may be used independently or simultaneously in accordance with the work 85 to be performed, but since the construction, arrangement and mode of operation of the spreader wing upon one side of the car is like unto that upon the other side, a description of one wing and its operating 90 mechanism will suffice for both.

The car may be constructed of metal or wood or in any approved manner.

Referring to the drawings, 1 represents the car trucks, 2 the rails, and 3, the car 95 under frame. I shall not describe the under frame in detail except to say that it is rigid frame work preferably formed of metal and upon which the floor 4, can be conveniently laid. Upon the floor of the 100 car, and extending longitudinally thereof along its sides, I have mounted channel members 5 and 6 upon which, if desired, mechanism can be mounted for movement longitudinally of the car. Inasmuch as this 105 mechanism may be of standard or desired construction it has not been illustrated nor will it be described. I might mention how-

ever, that the car is adapted to support what is known as a ditcher, being a machine adapted to the digging of ditches along the right of way, and for its convenient operation, being provided with wheels whereby the machine may move longitudinally of the car, using the channel members 5 and 6 as rails. This statement, I wish to be considered by way of illustration and 10 not by way of limitation. Secured in a vertical position at the side of the car and near the end, thereof, will be found a vertical column 7, which is provided with a groove 8 for guiding the wing post, 9. The wing 15 post 9 is provided at its outer end with parts 10 which co-operate with the hinge plate 11, of the wing, to form a vertical pivot which the pivot pin 12 completes. The heavy hinge plate 11 is suitably secured to 20 the spreader wing 13, which, during the operation of the car, serves to spread or displace the material along the road bed. Various conditions of road bed construction require that the spreader wing 13 be positioned at different elevations. The requirements also include the positioning of the wing at different distances from the side of the car, i. e. require that the wing be disposed at different angles. As the car is 25 propelled and the wing 13 comes into contact with the material to be spread, a great force operates to close the wing and it becomes necessary, therefore, to provide very rigid and substantial bracing members for transmitting the force to the car under frame. 30 At the same time these braces must be of such character as to permit the raising, lowering and swinging movement of the wing. The wing 13 and the parts connected 35 thereto are of very heavy and substantial construction and will fall of their own weight. I, therefore, depend upon gravity for lowering the wing and provide only for the raising thereof.

40 For raising the wing I provide an air engine 14, the piston rod 15, of which is connected to one end 16, of the rope or cable 17. The rope or cable 17 passes over suitable sheaves 18, 19 and 20, and the other end 21 is attached to the spreader wing 13, as by means of a bracket 22. When air is applied to the engine 14 the piston rod 15 moves from the extended position shown on the near side of the car in Fig. 1 to the position shown on the other side in Fig. 1, thus causing the elevation of the spreader wing, the post 9 sliding upwardly in the column 7 as before stated. To lower the wing, it is but necessary to let it fall by gravity. For 45 controlling the air engine 14, a valve 50 is provided, also pipe connections extending to an air reservoir (not shown).

50 All of the mechanism for swinging the wing to and from the side of the car and 55 for locking and holding the wing in desired

placed position is arranged below the car. The mechanism is of unique construction. Depending from the car under frame and transversely positioned of the car, I provide a plurality of I-beams 23, 24, 25, 26, 70 27, and 28. The I-beams 23 and 26, 24 and 27, 25 and 28 are in vertical alignment and are spaced somewhat apart. The upper I-beams are secured in the sills of the car and the lower ones are supported upon a sub- 75 structure 29. Mounted for sliding movement between the I-beams 23 and 24, and between the I-beams 26 and 27 will be found cross heads 30, and 31 which cross heads are secured together for simultaneous movement by means of a vertical connecting plate 32. Secured to the vertical plate 32 and arranged for sliding movement in angle members 33 and 34 carried, respectively by the I-beams 23 and 26, will be found a long 80 rack-like member 35. Along one side the rack 35 is provided with a depressed gear rack 36 for engagement with the teeth of the gear wheel 37. On the opposite side the gear wheel 37 meshes with a rack member 85 38 which is fixed to the car against movement. Mounted transversely of the car and in line with the gear wheel 37 will be found an air engine 39, the piston rod 40 of which, at its outer end, is connected to the gear 90 wheel 37. The connection is a pivotal connection such that the gear wheel 37 may rotate. Thus as the piston rod 40 moves from the inward position, its innermost position being, a position corresponding to that 95 shown for the mechanism operating the wing on the far side of the car to the position shown on the near side of the car, the member 35 is moved from a position at the far side of the car to a position in which it projects slightly outwardly from the inner side of the car as shown in Fig. 1. 100 In other words, as the gear wheel 37 is moved outwardly by the piston rod 40 and at the same time rolls upon the rack 38, a 105 movement equal to twice the movement of the piston rod is given to the member 35. Such movement of the member 35, obviously moves the cross-heads 30 and 31 a corresponding distance. The connected cross-heads 30 and 31 are operatively connected to the spreader wing 13 by means of bracing members or struts 41 and 42 which struts, in the present instance, take the form of I-beams having, at 110 their ends, hooks 43, which are suitably curved to permit placement in receiving brackets and at the same time permit the braces to swing from the downwardly extending angular position, in which they 115 repose when the wing 13 is at work, to the horizontal position in which they are positioned for swinging movement of the wing to and from the car and while the wing is 120 at rest in inoperative position along the side 125 130

of the car. The air engine 39, for controlling the swinging movements of the wing 13, is governed by the fourway valve 44 which is connected by the piping shown so that air 5 may be delivered at either end of the air engine and thus cause the movement of the piston therein in the desired direction. The air piping is connected to an air reservoir (not shown) which may be placed at any 10 desired position under the car.

When the wing is in inoperative position or at rest, as shown in the far side of the car in Fig. 1, the wing 13 is in its uppermost position and the bracing struts 41 and 15 42 are disposed in a horizontal position under the car. To place the wing into operative position as shown in Fig. 2, and on the near side of the car in Fig. 1, air is applied to move the piston rod 40 away from 20 the air engine which moves the braces 41 and 42 from a position completely under the car to one completely outside of the car but still in a horizontal position. Thereafter the wing may be dropped to desired 25 position. The replacement of the wing from operative position to inoperative position is substantially a reversal of the above operation except that the wing is positively lifted by means of the air engine 14. When the 30 wing is in its operative position it is necessary to hold the cross-heads 30 and 31 against movement as they take the thrust of the wing. To this end I provide a lock mechanism which comprises a rod 45 transversely positioned of the car and which is supported in members 46 (see Fig. 6) for sliding movement. For the purpose of 35 slidably moving the rod 45 a hand lever 47 is provided at the side of the car. The rod 40 45 is offset, as is shown at 48, and mounted in the member 46 will be found a sliding block 49. When the rod 45 is moved to the right, the block 49 is withdrawn to a position flush with the face 46' of the member 45 46 and when the rod 45 is moved in the opposite direction the block 49 is projected to the position shown in Fig. 6. In the movement of the cross-heads transversely of the car the connecting plate 32 slides in intimate 50 relation to the face 46' and when the cross-heads have reached the desired position the rod 45 is shifted to the position shown in Fig. 6, thus shifting the block 49 behind the plate 32 so that the plate and 55 cross-heads are prevented from sliding inwardly.

As it may be desired to lock the cross-heads at different points in order that the wing may be locked at different distances 60 from the side of the car, several of the locking blocks 49 are provided and the rod 45 is provided with several spaced offset portions 48 for actuating the respective blocks. The construction and operation being the 65 same no further statement will be necessary.

It should be noted that the mechanism for operating the wings upon both sides of the car is arranged in compact relation and that certain of the parts necessary for the operation of one wing serve also as a part 70 of the structure for operating the other wing. For example the central I-beams 24 and 27 serve as guides for the cross-heads utilized for operating both wings.

The mechanism shown is simple, positive, 75 and durable; it is all so positioned as to leave the upper part of the car free for any use that may be desired; it is positioned entirely under the car when the wings are closed so that the car may be operated along 80 the right of way without the necessity of the removal of any parts, and that the wings can be operated by the mere turning of an air valve, thus making the car as a whole substantially automatic in its operation. 85

Inasmuch as this disclosure will readily suggest to others modified structures whereby the substantial objects and purposes of my invention may be attained I do not wish 90 to be limited to the specific construction and arrangement herein shown and described, except only as may be necessary by limitations in the hereunto appended claims.

I claim:

1. The improvements herein described comprising a car in combination with a wing having its inner end pivoted thereto and wing swinging and holding means, disposed under the car, when the wing is in inoperative position said means including an operating brace connected to the wing and of a length approximately the width of the car. 100

2. The improvements herein described comprising a car in combination with a wing having its inner end pivoted thereto, a wing swinging and holding brace of a length at least equal to one-half the width of the car, and means for disposing said brace under the car. 105

3. The improvements herein described comprising a car in combination with a wing having its inner end pivoted thereto, a wing swinging and holding brace, means for disposing said brace under the car, and means for moving it to swing the wing from the car, said brace occupying an angular position with respect to the side of the car when the brace is in extended position. 115

4. The improvements herein described comprising a car in combination with a wing having its inner end pivoted thereto, a wing swinging and holding brace, means for disposing said brace under the car, means for moving it to swing the wing 125 from the car, and to return it thereto, said brace in the swinging operation assuming different angular positions with respect to the wing.

5. The improvements herein described 130

comprising a car in combination with a wing having its inner end pivoted thereto, wing swinging and holding means and means for raising the wing, all positioned under the car when the wing is in inoperative position, said wing swinging and holding means including a brace member formed and connected to assume different angular positions with respect to the wing when the wing is 10 swung.

6. The improvements herein described comprising a car in combination with a wing having its inner end pivoted thereto and vertically slideable thereat, a wing swinging and holding brace in distended position being angularly disposed with respect to the side of the car, means for disposing said brace under the car, and means for raising said wing.

20 7. The improvements herein described comprising a car in combination with a wing having its inner end pivotally attached to and vertically movable at the side of the car, and wing swinging and holding means disposed under the car when the wing is in inoperative position said means including a brace transversely disposed under the car in one position and extending angularly therefrom in another position.

30 8. The improvements herein described comprising a car in combination with the wing having its inner end pivoted thereto, a wing swinging and holding brace, and means for disposing said brace under and 35 transversely of the car said means including a member slideable transversely of the car substantially the width thereof and to which said brace is attached.

9. The improvements herein described 40 comprising a car in combination with a wing having its inner end pivoted thereto, a wing swinging and holding brace and means for disposing said brace under and transversely of the car, said means including 45 a fixed gear rack, a movable gear rack to which one end of said brace is connected, and a gear wheel interposed between and meshing with the fixed and movable gear racks, together with means for causing the 50 gear wheel to roll on the fixed rack.

10. The improvements herein described comprising a car in combination with the wing having its inner end pivoted thereto, a wing swinging and holding brace, and 55 means for disposing said brace under and transversely of the car, said means including a crosshead, to which one end of said brace is secured, crosshead guides, and means for causing sliding movement of said 60 crosshead.

11. The improvements herein described comprising a car in combination with the wing having its inner end pivoted thereto, a wing swinging and holding brace and 65 means for disposing said brace under and

transversely of the car, said means including a crosshead, to which one end of said brace is secured, crosshead guides, and an air engine operatively connected to cause reciprocatory movement of said crosshead whereby desired swinging movement of the wing is effected.

12. The improvements herein described comprising a car in combination with the wing having its inner end pivoted thereto, 75 a wing swinging and holding brace, and means for disposing said brace under and transversely of the car, said means including a crosshead, to which one end of said brace is secured, crosshead guides, an air 80 engine having a piston and piston rod and means operatively connecting the piston rod to the crosshead, said means being formed to cause movement of the crossheads equal to twice the movement of the piston.

13. The improvements herein described comprising a car in combination with the wing having its inner end pivoted thereto, a wing swinging and holding brace, and means for disposing said brace under and 90 transversely of the car, said means including a crosshead, to which one end of said brace is secured, crosshead guides, means for causing sliding movement of said crosshead, and means for locking the crosshead 95 against movement.

14. The improvements herein described comprising a car in combination with the wing having its inner end pivoted thereto, a wing swinging and holding brace, and 100 means for disposing said brace under and transversely of the car, said means including a crosshead, to which one end of said brace is secured, crosshead guides, an air engine operatively connected to cause reciprocatory movement of said crossheads whereby 105 desired swinging movement of the wing can be effected, and means for locking the crosshead against movement.

15. The improvements herein described 110 comprising a car in combination with the wing having its inner end pivoted thereto, a wing swinging and holding brace, and means for disposing said brace under and transversely of the car, said means including a crosshead, to which one end of said brace is secured, crosshead guides, and an air engine having a piston and piston rod and means operatively connecting the piston rod to the crosshead, said means being 115 formed to cause movement of the crossheads equal to twice the movement of the piston, and means for locking the crosshead against movement.

16. The improvements herein described 125 comprising a car in combination with a wing having its inner end pivoted thereto, wing swinging and holding means, disposed under the car, when the wing is in inoperative position, said means including a brace of a 130

length approximating the width of the car, and means for locking the wing swinging and holding means against movement.

17. The improvements herein described comprising a car in combination with a wing having its inner end pivoted thereto, a wing swinging and holding brace, means for disposing said brace under the car and substantially transversely thereof and for moving it outwardly and angularly, and means for locking the wing swinging and holding brace against movement.

18. The improvements herein described comprising a car in combination with a wing having its inner end pivoted thereto, a wing swinging and holding brace, and means for disposing said brace transversely of the car, said means including a fixed gear rack, a movable gear rack to which one end of said

20 brace is connected, and a gear wheel interposed between and meshing with the fixed and movable gear racks, together with means for causing the gear wheel to roll on the fixed rack.

25 19. The improvements herein described comprising a car in combination with the wing having its inner end pivoted thereto, a wing swinging and holding brace, and means for disposing of said brace transversely of the car, said means including a crosshead, to which one end of said brace is secured, crosshead guides, and means for causing sliding movement of said crosshead.

20. The improvements herein described comprising a car in combination with the wing having its inner end pivoted thereto, a wing swinging and holding brace, and means for disposing said brace transversely of the car, said means including a crosshead, to which one end of said brace is secured, crosshead guides, and an air engine operatively connected to cause reciprocatory movement of said crosshead whereby desired swinging movement of the wing is effected.

45 21. The improvements herein described comprising a car in combination with the wing having its inner end pivoted thereto, a wing swinging and holding brace, and means for disposing said brace transversely

of the car, said means including a crosshead, to which one end of said brace is secured, crosshead guides, an air engine having a piston and piston rod and means operatively connecting the piston rod to the crosshead, said means being formed to cause greater movement of the crosshead than of the piston.

22. The improvements herein described comprising a car in combination with the wing having its inner end pivoted thereto, a wing swinging and holding brace, and means for disposing said brace transversely of the car, said means including a crosshead, to which one end of said brace is secured, crosshead guides, means for causing sliding movement of said crosshead, and means for locking the crosshead against movement.

23. The improvements herein described comprising a car in combination with the wing having its inner end pivoted thereto, a wing swinging and holding brace, and means for disposing said brace transversely of the car, said means including a crosshead, to which one end of said brace is secured, crosshead guides, an air engine operatively connected to cause reciprocatory movement of said crosshead whereby desired swinging movement of the wing can be effected, and means for locking the crosshead against movement.

24. The improvements herein described comprising a car in combination with the wing having its inner end pivoted thereto, a wing swinging and holding brace, and means for disposing said brace transversely of the car, said means including a crosshead, to which one end of said brace is secured, crosshead guides, and an air engine having a piston and piston rod, and means operatively connecting the piston rod to the crosshead, said means being formed to cause movement of the crosshead equal to twice the movement of the piston, and means for locking the crosshead against movement.

In testimony whereof, I have hereunto set my hand, this 30 day of September, 1919.

ROBERT E. BRESSLER.
